Inventor.
By his Atty's,
Edson Bird.

UNITED STATES PATENT OFFICE.

THRON N. BERGER, OF ELGIN, IOWA.

APPARATUS FOR RETOUCHING NEGATIVES.

SPECIFICATION forming part of Letters Patent No. 253,834, dated February 21, 1882.

Application filed August 11, 1881. (No model.)

To all whom it may concern:

Be it known that I, T. N. BERGER, a citizen of the United States of America, residing at Elgin, in the county of Fayette and State of Iowa, have invented certain new and useful Improvements in Apparatus for Retouching Negatives; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a side elevation of my improved retouching-negative machine, and Fig. 2 is a detailed sectional view of the same.

This invention has relation to improvements in machines for retouching negatives, its object being to obtain by mechanism the motion for retouching the negative necessary to produce a fine stippled effect upon the negative. Heretofore this has been done by vibrating the negative-easel or the hand-rest, requiring 25 the employment between the drive-wheel and the easel or hand-rest of cams, crank-arms or levers, and belts and pulleys, which I dispense with.

To this end my invention consists in affecting 30 the negative itself directly by a roll or mechanism capable of imparting a vibratory motion to the negative, and in applying to the hand-rest an elastic holding-bar for the negative-plate, substantially as hereinafter more 35 fully set forth and claimed.

In carrying out my invention I employ, as will be seen by reference to the accompanying drawings, and as has heretofore been done, a frame, A, suitably supported at the desired elevation, and having hung therein a mirror, B, the purpose of which, as is known, is to enable the salient features of the negative to be well defined.

Hinged at one end to the base-frame A is 45 the negative-easel C, which is capable of being propped at the desired inclination by the pivoted prop or props a a.

D is the shade, pivoted or hinged to the upper end of the negative-easel, and propped in 50 position by the pivoted props b.

E is the hand-rest, hinged or flexibly connected to the easel-frame C, and, unlike the common rest, is provided upon its under side with an elastic bar, e, for holding yieldingly the lower or one end of the negative-plate, to 55 permit, while securing in position that end of the negative-plate, its partaking of the vibratory motion imparted thereto, as presently described.

F is a roll having any desired number of 60 ribs or corrugations, or otherwise constructed, that will adapt it to act upon the negative-plate G, which rests thereon, as shown, so as to impart to it a vibratory motion when the roll is revolved. With this motion, the operator 65 holding his pencil or instrument in a fixed position upon the negative, thus relieving the hand of action, as practiced in the old way, the hand is not only relieved of this tiresome motion, but the retouching of the negative is performed with greater uniformity, thereby imparting a finer stippled effect to the negative or picture. It will be further noticed that the roll acting directly upon the negative, all 70 cams, crank-arms or levers, pitmen, and pulleys and belts heretofore employed for operating the negative-easel or hand-rest are dispensed with.

F' F' are bearing plates or straps hinged at 75 one end to the upper side of the easel C, and resting upon the shaft of the roll F, and under 80 these plates may be made in the easel, at different intervals apart, bearing-sockets, to enable the roll to be adjusted according to the length or size of the negative-plate to be operated upon.

The roll-shaft-operating pulley f may be driven by belt or otherwise from any suitable motor. Upon its shaft is also an emery-wheel, g, for use as convenience may require.

A second elastic holding-bar, H, is connected to the hinged or pivoted bearing-plates F', and pressed by a spring or springs, g', fastened to the plates F', for yieldingly securing the upper end of the negative-plate.

I claim and desire to secure by Letters Patent—

1. The combination, with the negative-easel of a negative-retouching machine, of the ribbed corrugated roll or mechanism bearing directly 100

on the negative-plate, and adapted to impart to the said plate a vibratory motion, substantially as set forth.

2. In a negative-retouching machine, the hand-rest E, having the elastic holding-bar c, substantially as set forth.

3. In a negative-retouching machine, the combination, with the negative-easel C, of the ribbed, fluted, or corrugated roll F, hand-rest E, having the elastic bar c, and elastic bar H, substantially as and for the purpose set forth.

4. In a machine for retouching negatives, the

combination, with the negative-easel C and the roll F, of the pivoted or hinged bearing-plates F', covering two or more bearing-sockets in the easel, substantially as and for the purpose set forth.

In testimony whereof I affix my signature in presence of two witnesses.

THRON N. BERGER.
